OUTDOOR INDIRECT STREET LAMP

Luis F. Villa, 1727 Moravian St.,
Philadelphia, Pa. 19103

Continuation of design applications Ser. No. 3,042,
July 12, 1966; and Ser. No. 4,949, and Ser. No.
4,957, Dec. 7, 1966. This application June 2, 1967,
Ser. No. 7,719

Term of patent 14 years

(Cl. D48—31)

FIGURE 1 is a top plan view showing my new design; FIGURE 2 is an elevational view taken from the front thereof;

FIGURE 3 is an elevational view taken from the left rear thereof;

FIGURE 4 is an elevational view taken from the right rear thereof; and

FIGURE 5 is a cross-sectional view taken along line 5—5 of FIGURE 3 showing the underside of the reflector;

FIGURE 6 is a top plan view of a modified form of my design;

FIGURE 7 is a front elevational view thereof;

FIGURE 8 is an elevational view taken from the right side thereof; and

FIGURE 9 is an elevational view taken from the left side thereof;

FIGURE 10 is a top plan view of another modified form of my design;

FIGURE 11 is a front elevational view thereof;

FIGURE 12 is an elevational view taken from the right side thereof; and

FIGURE 13 is an elevational view taken from the left side thereof.

The base of my design is essentially plane and unornamented.

This application is a continuation of my co-pending applications Ser. No. D. 3,042 filed July 12, 1966, Ser. No. D. 4,949 filed Dec. 7, 1966 and Ser. No. D. 4,957 filed Dec. 7, 1966, all now abandoned.

I claim:

The ornamental design for an outdoor indirect street lamp, as shown and described.
